ASH TRAY

Josephine A. Porter, Baltimore, Md.

Application December 9, 1944, Serial No. 567,415

3 Claims. (Cl. 131—240)

This invention relates to ash trays and it consists in the constructions, arrangements and combinations herein described and claimed.

It is an object of the invention to provide an ash tray on which a lighted cigarette may be supported within the tray at an angle permitting ready grasp of the cigarette, as well as retaining the mouth-end of the cigarette from direct contact with the rest, thereby providing a sanitary support for the cigarette.

It is also an object of the invention to provide novel cigarette rests which are so constructed as to afford a frictional grip upon a cigarette, enabling the spacing of the lighted end from the base of the receptacle, preventing extinguishing of the cigarette, and in addition providing a means complementary to each of the rests for snuffing the lighted end of the cigarette when so desired.

It is a still further object of the invention to provide a new construction of rest in conjunction with a novel contour of rim which will insure movement of the cigarette into one of the rests in the event that the cigarette is positioned so as to contact the rim of the tray.

It is also an object of the invention to provide a tray which will be attractive as well as ornamental and practical to the end that lighted cigarettes will be positively retained against accidental displacement when positioned in the rests.

Additional objects, advantages and features of invention will be apparent from the following description and accompanying drawing, wherein

Figure 1 is a top plan view of an ash tray constructed in accordance with my invention.

Figure 2 is a side elevation thereof.

Figure 3 is a cross section on the line 3—3 of Figure 1.

Figure 4 is a cross section on the line 4—4 of Figure 1.

There is illustrated an ash tray generally indicated by the reference character 10, in the present instance shown of substantially square formation as viewed in top plan view, although such shape is not essential in obtaining the objects sought. The tray may be formed from glass, pottery, metal or other suitable material, and as shown each of the respective corners of the tray is provided with a cigarette rest 11 of novel construction, as will now be described.

The rests are of identical construction, each being molded or otherwise formed as an integral part of the upper or rim portion of the tray. As may be seen in Figure 1, the corners are formed substantially in the shape of a horse-shoe, the

5 toe portion 12 defining the outer peripheral portion of the rest, and the quarter portions 13 being directed inwardly upon the tray and merging into inwardly curved portions 14 defining respective side walls 15 of the tray. The upper edges of the side walls 15 are rounded, as indicated at 16, for a purpose presently to be described.

10 As shown in Figure 1, the quarter portions 13 converge toward each other in the direction of the center of the tray, the heel members 17 being spaced apart approximately the width of a cigarette, or slightly less so that a cigarette may be laid within the space between the heel members 17 for temporary support, the lighted end 15 of the cigarette resting within a well 18 formed in the base of the tray. If a lighted cigarette was allowed to remain in such position over a period of time, the lighted end would become extinguished due to contact with the base of the well but where it is desired to maintain the cigarette lighted, the cigarette may be positioned between the heel portions 17 so as to obtain a gripping action on the sides thereof and maintain the lighted end in raised position with respect to the 20 base of the well. If the cigarette remained in this position for a period of time it would continue to burn up to the point of contact with the heel portions of the rest where the compressive action between the heel members and the cigarette 25 would be sufficient to snuff the cigarette.

25 As may be seen in Figure 1, a well 18 is complementary to each of the rests and in alignment with a medial line through the rests. The wells 18 are shown as of substantially oval formation, their innermost ends being formed with an overhanging lip or edge 20. The lip 20 may be employed as a scraper device for removing the lighted end of a cigarette by drawing the lighted end against the edge.

30 By providing the rounded edge 16, it will be apparent that if a cigarette is laid thereagainst this surface will tend to cant or divert the cigarette toward one of the rests, thus preventing the cigarette from falling outwardly of the tray.

35 For the purpose of ornamentation as well as a means for locating a tray in a darkened room the openings representing the nail holes of a horse-shoe may be filled with a luminous material 21, making each rest clearly discernible 40 when viewed from above the tray. In addition, a circumscribing groove 22 may be formed adjacent the base of the tray for reception of a luminous material.

45 It will be apparent that if desired, a cigarette may be disposed through the opening 19, the

lighted end resting within the well 18 aligned with said opening.

While I have shown and described a preferred form, this is by way of illustration only, and I consider as my own all such modifications in construction as fairly fall within the scope of the appended claims.

I claim:

1. An ash tray comprising a receptacle having a substantially square base and upstanding side walls inwardly curved to lie over the base for a major portion of the lengths of said walls, the upper terminal edges of said walls at respective corner junctions being substantially in the form of a horse-shoe, the heel portions of which form a restricted passage for frictional engagement with a cigarette positioned therebetween, and a well member aligned with each restricted passage.

2. The structure of claim 1, in which each well member is formed with an overhanging lip in opposed relation to said restricted passages.

3. An ash tray consisting of a receptacle having a substantially square base, and side walls, the corner junctions of said side walls being formed substantially in the shape of a horse-shoe providing an opening between the quarter portions defining the horse-shoe for free reception of a cigarette, said quarter portions being directed inwardly over the base and merged with respective adjacent side walls to define respective heel members, said heel members being spaced apart a distance less than the thickness of a cigarette for frictional engagement with the cigarette when placed therebetween, the wall portions between next adjacent quarter portions being inwardly curved to lie over the base a substantial distance, the terminal edges of said walls being round and well members formed in said base, aligned through the medial axis between said quarter portions.

JOSEPHINE A. PORTER.
